[54] VELVET FABRIC WITH RANDOMLY GAPPED
PILE FACE
3 Claims, 3 Drawing Figs.

[52] U.S. Cl. 139/402
[51] Int. Cl. D03d 27/10

ABSTRACT: A velvet or plush pile fabric having random gaps in the pile face thereof formed by spaced slubs in slab filling yarns which alternate with plain filling yarns throughout the length of the fabric.

Patented Nov. 24, 1970

3,542,086

VELVET FABRIC WITH RANDOMLY GAPPED PILE FACE

As is well known, velvet fabrics generally are woven on plush looms which weave two superposed layers of ground fabric simultaneously while interlacing warpwise pile yarns between the two layers, after which the pile yarns are severed while still on the loom by a reciprocating knife blade, thus forming two separate pieces of velvet fabric. Plain twisted yarns are generally used as filling yarns in velvet fabrics.

In order to impart an antique appearance to the two velvet fabrics, slab yarns provided with spaced slubs of regular or irregular lengths have been used as filling yarns throughout velvet fabrics. Velvet fabrics woven with slab filling yarns have randomly arranged gaps or fissures formed in the pile faces thereof by virtue of the fact that the slubs separate the adjacent legs of those tufts extending along beside the slubs. Such gaps present an appearance of short random fillingwise streaks throughout the face of the fabric.

Probably due to the fact that up until quite recently the filling yarns were inserted in the two layers of fabric being woven on a plush loom by bobbin-carrying shuttles whose bobbins had to be replaced by an operator upon exhaustion of the filling thereon, it has been conventional practice for many years to weave such antique velvet fabrics from filling yarns which were entirely of the slab type. As is well known, slab yarns are considerably more expensive than plain twisted yarns of similar fibers. Thus, such antique velvet fabrics have been considerably more expensive to produce than the plain velvet fabrics whose filling yarns are of the plain twisted type.

More recently, shuttleless plush looms have been developed wherein filling yarns are inserted in respective upper and lower warp sheds by a pair of upper and lower reciprocating filling-drawing rapiers or needles. A typical shuttleless plush loom is disclosed in U.S. Pat. No. 3,394,739, issued July 30, 1968, of common assignee. We have now discovered that the cost of manufacture of antique velvet fabrics having slab yarns therein can be substantially reduced by weaving the same on shuttleless plush looms and by equipping such shuttleless plush looms with a filling mixer arranged to alternate in presenting plain yarn and slab yarn to the two filling-drawing rapiers so that on alternate shots of the rapiers, the slab yarn is presented to one of the rapiers as the plain yarn is presented to the other rapiers, and on intervening shots of the rapiers, the plain yarn is presented to said one of the rapiers and the slab yarn is presented to the other rapiers. This results in each layer of velvet fabric having slab filling yarns therein alternating with plain filling yarns throughout the length thereof so that one-half of the filling yarn in the fabric may be of the slab type and the other expensive, of the filling yarn may be of the less expensive, plain twisted type, thereby greatly reducing the cost of the filling yarn required to manufacture a given length of antique velvet fabric.

It is therefore an object of this invention to provide an improved antique velvet fabric characterized by having randomly spaced gaps or fissures in the pile face thereof, and which fabric may be produced more economically than prior art types of velvet fabrics having such gaps or fissures in the pile face thereof.

It is a more specific object of the invention to provide an antique velvet fabric in which ground warp yarns are interwoven with plain filling yarns and slab filling yarns arranged in alternation throughout the length of the fabric, with pile yarns looped beneath the plain and slab filling yarns, wherein the pile yarns are severed to form short tufts projecting a predetermined distance from one face of the interwoven warp yarns and filling yarns, and also wherein the slubs in the slab filling yarns serve to form gaps or fissures in the pile face of the fabric.

The fabric of this invention may be produced economically on a loom of the type disclosed in said U.S. Pat. No. 3,394,739 by weaving upper and lower superposed fabric layers with interconnecting pile yarns therebetween and inserting and beating up a plain filling yarn and a slab filling yarn in respective upper and lower sheds of ground warp yarns while shedding at

least some of the pile yarns over the plain filling yarn; then the position of the ground warp yarns is reversed in the respective upper and lower warp sheds and a plain filling yarn and a slab filling yarn are then inserted and beaten up in the respective lower and upper warp sheds while shedding at least some of the previously raised pile yarns below the plain filling yarn. The steps then may be repeated in the order prescribed to form the desired length of double-layer fabric with pile yarns interlaced therebetween, after which the pile yarns are severed about half-way between the two layers of fabric to form two separate layers of fabric each having alternate lengths of slab filling yarn and intervening lengths of plain filling yarn therein, the slubs of the slab yarn then serving to define gaps or fissures in the pile tufts thus formed in each fabric layer.

Some of the objects of the invention having been stated, other objects will appear as the description proceeds when taken in connection with the accompanying drawings, in which

FIG. 1 is a fragmentary plan view of a piece of antique velvet fabric showing fillingwise streaks formed in the pile face thereof according to the present invention;

FIG. 2 is an enlarged fragmentary view of a portion of the fabric shown in FIG. 1, particularly showing how the slubs of the slab yarn form gaps or fissures in the pile face of the fabric; and

FIG. 3 is an enlarged fragmentary cross-sectional view taken substantially along line 3-3 in FIG. 2 and showing, in particular, how a slab in a corresponding yarn forms a gap or fissure in the pile face of the fabric.

Referring more specifically to the drawings, the improved velvet fabric produced in accordance with this invention is broadly indicated at 10 in FIGS. 1-3 and comprises a ground fabric or base woven from a plurality of ground warp yarns 11 interwoven with alternating first and second cut lengths of filling yarn 12, 13 beneath which transverse rows of relatively short cut pile tufts 14 are looped. The yarns 11, 12, 13 and tufts 14 may be spun from cotton, rayon or other textile fibers, as desired. All the filling yarn lengths 12, 13 may be of generally about the same size, with the important exception that each first filling yarn length 12 is a plain twisted yarn of substantially uniform size throughout its length, and each second filling yarn length 13 is in the form of a slab yarn having regularly or irregularly spaced slubs or enlarged portions 15 along its length. The slubs 15 may be of the same or different lengths as desired.

As is usual, the base of the fabric is tightly woven so that the pile tufts 14 substantially cover and obscure the ground warp yarns and filling yarns throughout the fabric. However, whenever a slab 15 is present in the fabric, those legs of the tufts positioned along opposite sides of the respective slubs are spread apart by the slubs as best shown in a somewhat exaggerated manner in FIGS. 2 and 3. Thus, although the pile tufts 14 may substantially obscure the slubs, the slubs cause the free end portions of the adjacent pile tufts to be spread apart sufficiently to define respective fillingwise streaks, gaps or fissures 15a throughout the pile face of the fabric as shown in FIG. 1.

It will be noted that by providing a plain filling yarn length 12 between each adjacent pair of slab filling yarn lengths 13, the fabric of this invention may be produced more economically than would be the case if all the filling yarn lengths were formed of slab yarn, as has been the case heretofore. Even though plain filling yarn lengths 12 are used in alternation with slab filling yarn lengths 13 in the instant fabric, the fabric does not differ materially in appearance from an antique fabric whose filling yarns are all of the slab type.

The improved velvet fabric 10 may be woven on a shuttleless plush loom of the type disclosed in said U.S. Pat. No. 3,394,739, issued July 30, 1968, to which reference is made for a detailed disclosure thereof. As disclosed in said patent, such a loom includes a pair of lower and upper filling-drawing rapiers which are reciprocated in front of an oscillating reed into and out of respective lower and upper warp sheds formed

from respective groups of ground warps for inserting cut lengths of filling yarn in the respective sheds. In so doing, the rapiers also insert corresponding lengths of filling yarn within a common shed formed of pile yarns of which the pile tufts 14 of FIGS. 1, 2 and 3 are formed.

Thus, the fabric 10 described with respect to FIGS. 1, 2 and 3 may constitute a lower fabric layer woven simultaneously with an upper fabric and during which the lower and upper pile yarns are alternately interwoven with the lower and upper fabric layers, resulting in the pile yarns being interlaced between the lower and upper fabric layers. As the fabric layers are advanced forwardly by suitable takeup means, the pile yarns are severed about halfway between the two fabric layers by means of a transversely reciprocating knife blade to form two separate layers of velvet fabric therefrom.

As heretofore described with respect to FIGS. 1-3, the fabric 10 has alternate lengths of plain filling yarn 12 and intervening lengths of slab filling yarn 13 interwoven with the ground warps 11 to form the base of the fabric. By utilizing a suitable filling mixer arranged to alternate in presenting plain yarn and slab yarn to the two lower and upper filling-drawing rapiers of said patent as stated earlier herein, it can be seen that each layer of fabric produced on the loom will have slab filling yarns therein alternating with plain filling yarns throughout the length thereof, as described with respect to the fabric 10 of FIGS. 1, 2 and 3.

It is thus seen that I have provided an improved antique velvet fabric wherein the fabric is provided with randomly spaced gaps or fissures in the pile face thereof, the effect of which may be produced more economically than prior art types of antique velvet velvet fabrics having such gaps or fissures therein.

In the drawings and specification, there have been set forth preferred embodiments of the invention, and although specific terms are employed, they are used in a generic and descriptive sense only and not for purposes of limitation, the scope of the invention being defined in the claims.

We claim:

1. An antique velvet pile fabric comprising a base of ground warps interwoven with plain filling yarns and slab filling yarns arranged in alternation throughout the fabric, warpwise rows of tufts of pile yarn looped beneath each of said filling yarns and forming a velvet pile face on the fabric, alternate rows of tufts being looped beneath alternate filling yarns and intervening rows of tufts being looped beneath intervening filling yarns, each slab filling yarn including along its length a plurality of elongate, spaced apart, enlarged slubs of varying length serving to spread apart corresponding tufts looped therebeneath to define elongate spaced apart gaps in the pile face, and said plain filling yarns being of substantially uniform size throughout their lengths and of considerably smaller size than the slubs of said slab filling yarns, whereby the use of said plain filling yarns and said slab filling yarns in alternation substantially reduces the usual quantity of slab yarn required.

2. An antique velvet fabric according to claim 1, wherein the slubs are spaced varying distances apart along the length of each slab filling yarn.

3. An antique velvet pile fabric comprising a base of ground warps interwoven with plain filling yarns and slab filling yarns arranged in alternation throughout the fabric, warpwise rows of tufts of pile yarn looped beneath each of said filling yarns and forming a velvet pile face on the fabric, alternate rows of tufts being looped beneath alternate filling yarns and intervening rows of tufts being looped beneath intervening filling yarns, each slab filling yarn including a plurality of elongate enlarged slubs spaced varying distances apart along its length and serving to spread apart corresponding tufts looped therebeneath to define elongate spaced apart gaps in the pile face, and said plain filling yarns being of substantially uniform size throughout their lengths and of substantially the same size as those portions of said slab filling yarns between adjacent slubs thereof, whereby the use of said plain filling yarns and said slab filling yarns in alternation substantially reduces the usual quantity of slab yarn required.

UNITED STATES PATENT OFFICE
CERTIFICATE OF CORRECTION

Patent No. 3,542,086

Dated November 24, 1970

Inventor(s) Walter J. Crenshaw and Hoke S. Hicks

It is certified that error appears in the above-identified patent and that said Letters Patent are hereby corrected as shown below:

Column 1, line 50, "expensive," should be --half--; same column line 66, "wrap" should be --warp--. Column 3, line 8, after "fabric" insert --layer--; same column line 32, "velvet velvet fabrics" should be --velvet fabrics--.
